UNITED STATES PATENT OFFICE.

EDWARD A. GEORGE, OF SHREVEPORT, LOUISIANA.

ROTARY BIT.

1,388,424.

Specification of Letters Patent. Patented Aug. 23, 1921.

Application filed June 27, 1919. Serial No. 307,098.

To all whom it may concern:

Be it known that I, EDWARD A. GEORGE, a citizen of the United States, residing at Shreveport, Caddo parish, Louisiana, have 5 invented a certain new and useful Improvement in Rotary Bits, of which the following is a full, clear, and exact description, such as will enable others skilled in the art to which it appertains to make and use the

10 same.
My invention relates to rotary drills of the roller type for use in drilling oil, water, and gas wells, and mines. In this type of drill the bit is attached at the lower end of a 15 hollow drill stem which is rotated to cause the cutters on the forward end of the bit to roll on the bottom and sides of the hole and thus disintegrate the material which is washed upwardly to the surface of the 20 ground by means of a stream of flushing water pumped downwardly through the hollow drill stem and through channels in the bit itself to the bottom of the hole.

An object of my invention is to provide 25 a bit of the roller type which has cutters thereon of novel construction, the said cutters being angular in form and adapted to rotate on approximately upright shafts in the lower head of the bit.

30 Another object is to provide a plurality of cutters mounted on the lower end of the bit in such manner as to most efficiently dig into the material at the bottom of the hole and to preserve the gage at the side of the 35 hole.

Another object is to so mount the cutters 40 that the thrust of the cutting action will be efficiently taken up in the head of the bit without danger of breaking or mutilation of the cutters.

Other objects and advantages will more 45 clearly appear in the specification which follows and will be emphasized with more particularity in the claims attached hereto.

45 Referring to the drawings forming a part of this specification, and wherein like parts are designated by like numerals throughout the several views, Figure 1 is a central longitudinal section through the head of my 50 improved bit; Fig. 2 is a bottom plan view thereof; Fig. 3 is a central longitudinal section of the same, taken at right angles to the view shown in Fig. 1; Fig. 4 is a side elevation of the invention; Fig. 5 is a transverse section through the head of my bit 55 taken on the plane 5—5 of Fig. 1; Fig. 6

is a top plan view of the shank of my bit showing the position of the water and oil ducts therein; Fig. 7 is a central longitudinal section through a different embodiment 60 of my invention; Fig. 8 illustrates a different means for mounting the cutter shaft in the head of the bit; and Fig. 9 is a still different embodiment of one of the cutters used in my invention. 65

My improved bit is made up of a head 1 somewhat cylindrical in shape and having a plurality of longitudinal flutes or grooves 2 in the outer periphery thereof, as shown in Figs. 2 and 5, to accommodate the flow of 70 flushing water past the head of the bit. The head 1 has an upwardly extending shank 3 of reduced diameter, threaded at 4 for attachment to a drill collar. The lower face of the head is provided with four cutters. 75 Two of these cutters are inclined slightly outward at the bottom, forming an upright cutting portion to act upon the outer periphery of the hole and to maintain the gage thereof. Two intermediate cutters 6 are in- 80 clined inwardly at their lower ends so as to cut away the central portion of the bottom of the hole. By reference to Fig. 2 it will be seen that the outer cutters 5 and the inner cutters 6, are so positioned that when the 85 bit is rotated the combined effect of the cutters will be to act upon the whole surface of the bottom of the hole and to drill into the material at all points.

The cutters shown in my improved bit are 90 somewhat elongated in formation and angular in outline so as to provide four side cutting teeth 7 on each cutter. These teeth are inclined slightly inward toward the lower end, forming cutters of an approximately 95 frusto-pyramidal form. The lower truncated end of the pyramid is also tapered slightly to a point at 8, and the teeth on the side of the cutters are continued abruptly inward to this point. Between the four 100 teeth 5 of each cutter, the side of the cutter is fluted or grooved at 9 so as to provide a better cutting point at each angle thereof. The inclination of the two outer cutters 5 is such that the inclined or tapered face at the 105 outer sides of the cutters shall be in parallel relation with the side of the hole. In other words, the side teeth 7 are parallel with the side of the head 1, but are so mounted as to project somewhat beyond the sides of the 110 head in order to cut a hole of larger diameter than the head of the bit so that there

will be no tendency of the bit to wedge or lodge in the hole.

The two intermediate cutters 6 are shaped identically like the cutters 5. The inclination of the inner cutters, however, is toward the center of the head, and the angle is such that the side faces are vertical along the line of the central axis of rotation of the bit. This fact is shown particularly in Fig. 3. 10 The inward edges of these two cutters are spaced somewhat apart, however, to allow them to rotate freely. They are close enough together, however, so that with the ordinary vibration or whipping action, 15 which takes place as a drill bit is rotated, the cutters will serve to prevent the formation of a core at the center of the bit.

The upper shank 10 of each of the cutters is cylindrical in shape and of reduced diameter. This shank is preferably threaded 20 to accommodate a bearing sleeve 11 thereon. Said sleeve is of hardened material and is provided at a point intermediate the ends with a peripheral groove 12, into which a set 25 screw 13, or similar holding means, is fitted to allow rotation of said cutter, as shown particularly in Fig. 1. The bearing sleeve is adapted to seat rotatably within an outer journal bearing 14 within the socket 15 in 30 the head. At the upper end of the shank 10, and journal 14, is an anti-friction washer 16 fitted within the socket 15 and forming a thrust bearing for the upper end of the rotating cutter.

35 These bearings are the same in each of the cutters of my preferred embodiment. Lubricant is supplied to the bearings from a central upper channel or container 17 in the head of the bit. This channel is filled with 40 lubricant and the upper end is closed by means of a threaded plug 19 to prevent the entrance of water or other material therein. Branching ducts 20 lead from the lower end of this channel to the upper bearing washer 45 16 and through a registering channel therein to the bearing surface of the cutter.

Flushing water is supplied to the cutters through two channels 21 leading from the upper ends of the shank of the bit downwardly in an inclined direction for a distance, and then directly downward to issue at a point in advance of each of the side cutters 5. The central cutters 6 are supplied with water through a central water channel 55 22, which receives its water from an inclined channel 23 leading from the upper end of the shank downwardly at an inclination to the upper end of the channel 22. By means of these water channels, a stream of water is 60 discharged immediately in front of each of the side cutters 5 and immediately between the two central cutters 6 so that the cuttings will be washed away from the cutting points of the bit and thus not impede its progress

or cause the balling up of the cutters in soft 65 material.

Under ordinary circumstances cutters constructed in conformance with the disclosure above set forth will act to maintain the gage of a hole uniformly with very little wear 70 upon the cutters. I have, however, provided, in the two sides of the head, in a position at right angles to the side cutters 5, a pair of scraping reamers 24. These reamers comprise scraping chisel blades, dovetailed at their inner sides at 25 to fit slidably within longitudinal grooves 26 in the sides of the head. They are retained against longitudinal movement within these slots by means of set screws 27. These blades project 75 from the side of the head for a distance such that when the sharp edges 7 of the cutters 6 have been worn slightly the reaming blades will engage the side of the hole and will assist in maintaining the gage of the 80 hole and therefore prevent the wedging of the head therein.

In Fig. 7 I have shown a modified form of bearing and a modified means for lubrication. The bearing sleeve 11' is threaded 90 onto the shank 10 of each of the cutters in the same manner as previously described. It has, however, a lower laterally extending flange 28, the upper face of which acts as a seat for packing washers 29. The outer 95 journal sleeve 14' is also laterally extended at 30 and provided with an annular inner recess to receive the said packing washers 29, and thus maintain a fluid-tight bearing 100 against the entrance of foreign material thereto. There is also a roller bearing 38 arranged between the upper face of the shank 10 of the bit and the bearing washer 16' at the upper end thereof. This roller bearing serves to take up the upward thrust 105 of the cutting action in a more efficient way and will assist in the easy operation of the cutters.

The lubricant in this operation is contained in separate channels 31, bored in the 110 sides of the bit, as shown in Fig. 7, and closed at the upper end by threaded plugs 32. These channels are filled with lubricant when the bit is introduced into the hole, which lubricant gradually passes downward 115 through ducts 33, through the thrust washer 16' and registering channels 34, in the upper part of the shank 10, these channels having laterally branching portions conducting the lubricant to the side of the bearing sleeve 120 11', as shown in the drawing. This form of bearing is otherwise the same as that previously described and will need no further explanation. It has some advantage, however, over the previously described bearing, 125 in that the lubricant is retained upon the bearing by means of the packing washer 29, and the roller bearings tend to give the cut-

ters a freer rotation than the ordinary bearing. Flushing water is supplied to the cutters in this embodiment through a single central channel 22'.

5 In Fig. 8, the bearing sleeve is omitted and I have used an outer journal sleeve 14'', similar to that disclosed in the previous modifications. There is, however, a recess on the inner face of the journal sleeve into 10 which packing washers 29'' may be threaded. The shank of the bit is retained within the bearing in this modification by a threaded engagement with the upper washer 16''. This engagement is by means of a central 15 downwardly projecting screw portion 35 on the said washer, this screw being threaded into engagement with the upper end of the shank 10'', as shown. In assembling this 20 form of cutter, the washer 16'' is placed within the socket in the head and the journal 14'' is then threaded in place so as to retain the washer in position in the socket. The cutter is then fitted within the journal sleeve and rotated in a left-hand direction 25 and threaded upon the screw portion 35 of the washer. The rotation of the bit is ordinarily in a right-hand direction and this causes the cutters to roll in the same direction, thus preventing the tendency of the 30 cutter to unscrew from the washer 16'', and become lost in the hole.

In Fig. 9, I have shown a cutter with a bearing similar to that shown in Fig. 7, but with the ball-race omitted. The flushing 35 water is supplied in this modification directly to the sides of the cutters themselves through channels 36 in the head, these channels being inclined downwardly to pass through the thrust washer 16 and the shank 40 10 of the cutter to the central portion thereof, and from thence through branching ducts 37 to the outer grooves 9 in the faces of the cutters. This means of flushing the 45 cutters free of the detritus has some advantages in that the water impinges directly against the material being cut by the bit, and this will more efficiently clear the cutters of all disintegrated material.

The lubrication for this type of cutter is 50 similar to that shown in Fig. 7, there being lateral containing chambers 31' from which small ducts 33' conduct the lubricant downwardly to the upper face of the thrust washer 16'.

55 In assembling the cutters in my preferred form of bit, the thrust washers 16 are fitted within the socket 15 in the head, the journal sleeves 14 are then inserted therein, the bearing sleeves 11 are threaded over the upper 60 shank 10 of the cutters and introduced within the journal sleeve 14'. The set screws 13 are then threaded through the journal sleeves 14 into the grooves 12 in the bearing sleeves 14. The screws thus serve to retain 65 the journal sleeves 14 in place and also retain

the cutters within the journal sleeve, the said set screws fitting loosely within the groove 12 so that the cutters may rotate within the journal.

The bit is then threaded to the lower end 70 of the drill stem and the bit is ready for operation. The drill is rotated in a right-hand or clock-wise direction, as viewed from above, and when the same is rotated the cutters are rolled upon the bottom and sides 75 of the hole. This rolling movement will give a rotation to the cutters, acting to dig into the bottom of the hole with the forward cutting faces and to shear away the material from the sides and bottom of the hole with 80 the lateral cutting edges 7. This type of bit will be found to be very efficient in operation as the cutters are adapted to act upon the bottom of the hole with a sharp scraping action, and the sides of the cutters act 85 to maintain the gage of the hole at the sides thereof. Furthermore, the thrust of the cutting action is directed inwardly toward the head of the bit in such manner that the force of this thrust is taken up efficiently 90 in the bearings in the head so that there will be little tendency for breaking or wear on the operative parts.

Having thus described my invention, the further advantages of which will be obvious, 95 what I claim as new and desire to protect by Letters Patent is:

1. In a rotary boring drill, a head, approximately upright cutters rotatable in sockets in the forward face of said head, 100 and having a tapered forward cutting face and laterally tapered cutting edges so arranged that one side thereof is parallel with the sides of the bore being drilled, the other face being adapted to cut the bottom of the 105 hole and each cutter positioned to bear upon the bottom of the hole.

2. In a rotary boring drill, a head, four approximately upright cutters of uniform size mounted on pins rotatable in sockets in 110 the lower end thereof, said cutters being approximately pyramidal in shape to provide four longitudinal cutting teeth on the sides and four radial teeth on the forward face thereof, said cutters arranged to drill a cylindrical hole.

3. In a rotary boring drill, a head, approximately upright cutters projecting from the forward end of said head, said cutters being approximately rectangular in transverse section and having four inclined longitudinal side teeth and forward cutting faces adapted to act upon the bottom and sides of the hole being drilled, the longitudinal side teeth of one set arranged parallel with the 125 side of the hole and adapted to cut both the side and bottom of the hole.

4. In a rotary boring drill, a head having approximately upright bearing sockets in the forward end thereof, forwardly projecting 130

- cutters formed on shafts rotatable in said sockets, said cutters being approximately frusto-pyramidal in shape, the side faces of said cutters adapted to shear away the material from the sides and bottom of the hole, and forward cutting faces on said cutters adapted to drill the bottom of the hole, one side of each of said cutters being arranged parallel with the sides of the hole.
- 10 5. In a rotary boring drill, a head, four cutters of uniform size symmetrically arranged on the base thereof to drill a cylindrical hole, said cutters having integral shafts rotatable in sockets in the said head, two of said cutters being inclined slightly inwardly toward the central axis of the head to cut the central portion of the bottom of the hole, and two cutters inclined slightly outwardly away from said central axis to cut both the bottom and sides of the hole.
- 15 6. In a rotary boring drill, a head with bearing sockets in the base thereof, polygonal cutters mounted on integral shafts projecting upwardly into said sockets, bearing plates in the ends of said sockets to take up the thrust at the upper ends of said shafts, and longitudinal teeth on the four corners of
- 20
- 25

said cutters arranged to cut the full bottom and the sides of the hole.

7. In a rotary boring drill, a head, cutter shafts mounted in sockets therein, cutters integral with said shafts, said cutters being approximately pyramidal in shape, a longitudinal tooth at each corner thereof, a groove between said teeth, and the said shafts being so inclined as to bring said teeth on one side of each cutter into parallelism with the side of the hole.

8. In a rotary boring drill, a head having bearing sockets in the base thereof, said sockets inclined slightly from the vertical axis of the head, tapered cutters mounted on integral shafts journaled in said sockets, longitudinal teeth on the tapered sides of said cutters, the cutters and said teeth being so inclined and positioned as to have one side face parallel with the vertical axis of the head, and a tapered forward cutting face on each cutter for the purpose described.

In testimony whereof, I hereunto affix my signature, this the 24th day of June, A. D., 1919.

EDWARD A. GEORGE.
